DESIGN FOR EYEGLASSES

Beatrice S. Norton, Los Angeles, Calif.

Application August 3, 1944, Serial No. 114,715

Term of patent 7 years

(CL. D57—1)

To all whom it may concern:

Be it known that I, Beatrice S. Norton, a citizen of the United States, residing at Los Angeles, in the county of Los Angeles and State of California, have invented a new, original, and ornamental Design for Eyeglasses, of which the following is a specification, reference being had to the accompanying drawing, forming a part thereof.

Figure 1 is a front perspective view of a de-

sign for eyeglasses showing my new design and Figure 2 is a front elevational view thereof.

The essential features of my design reside in the type and arrangement of the jewels on the eyeglass front and temples as shown.

I claim:

The ornamental design for eyeglasses, substantially as shown and described.

BEATRICE S. NORTON.
